(57) CLAIM

The ornamental design for a bag, as shown and described.

DESCRIPTION

FIG. 1.1 is a front perspective view of the bag showing our new design;

FIG. 1.2 is a front view thereof;

FIG. 1.3 is a back view thereof;

FIG. 1.4 is a right side view thereof;

FIG. 1.5 is a left side view thereof;

FIG. 1.6 is a top view thereof; and

FIG. 1.7 is a bottom view thereof.

The dashed lines indicate stitching that forms part of the claimed design.

The dotted broken lines in the drawings represent environmental matter that forms no part of the claimed design.
